(57) **CLAIM**

The ornamental design for a cart, as shown and described.

DESCRIPTION

FIG. 1 is a front perspective view of a cart showing my new design;

FIG. 2 is a side elevation view of the right and left sides, which are mirror images, of FIG. 1.

FIG. 3 is a front side elevation view of FIG. 1.

FIG. 4 is a back side elevation view of FIG. 1

FIG. 5 is a top plan view of FIG. 1; and,

FIG. 6 is a bottom plan view of Figure. 1.

The broken line showing of the wheels is included for the purpose of illustrating environment and forms no part of the claimed design.

1 Claim, 5 Drawing Sheets
